UNITED STATES PATENT OFFICE

WILLIAM A. CROSS, OF EAST MILTON, MASSACHUSETTS

SECTIONAL LIQUID-HEATING APPARATUS

Application filed May 7, 1928. Serial No. 275,603.

This invention relates to improvements in sectional liquid heating apparatus and the principal object thereof is to provide a heating apparatus formed in sections adapted to be readily assembled and which when assembled will provide means for transmitting a maximum amount of heat to the liquid.

A further object of the invention is to provide a heating apparatus of this character comprising a plurality of members having chambers for the liquid to be heated and in which the walls of said members will present a maximum amount of surface to the heating flames and to the hot products of combustion.

15 A further object of the invention is to provide a heating apparatus comprising a fire-box having inner and outer surrounding water legs with a space therebetween forming a flue for the products of combustion, with a suitable hollow dome superimposed upon 20 said water legs and communicating therewith, and operable to direct the products of combustion downwardly through the flue which is located between the inner and outer 25 water legs.

A further object of the invention is to provide an apparatus of the character last described with additional capacity by providing one, or preferably a plurality of, wall sections 30 comprising inner and outer communicating hollow walls with means for establishing communication between the chambers of said walls and said water legs.

A further object of the invention is to provide means for further increasing the capacity 35 of the apparatus by providing one, or preferably a plurality of heating units mounted upon the fire-box and having radially extending chambers having walls presenting a large 40 heat-absorbing area, with said chambers communicating both with the water legs and with the dome of the heating apparatus.

A further object of the invention is to provide an apparatus of the character described 45 with means for preheating the air which is admitted to support combustion, this preferably being accomplished by conducting the air through a conduit which extends through a portion of the stack leading from the flue 50 of the heating apparatus.

A further object of the invention is to provide a construction of the character described in which the various sections of the apparatus may be readily assembled and communication established between the water chambers of 55 the various sections by means of push nipples.

These and other objects and features of the invention will more fully appear from the following description and the accompanying drawings, and will be particularly pointed out in the claims.

A preferred embodiment of the invention is illustrated in the accompanying drawings, in which,

Fig. 1 is a central vertical sectional view of 65 a liquid heating apparatus;

Fig. 2 is a transverse sectional view on line 2-2 Fig. 1;

Fig. 3 is a transverse sectional view on 70 line 3-3, Fig. 1;

Fig. 4 is a side elevation of the heating apparatus shown in Fig. 1 partly broken away and illustrating in section particularly a portion of the stack and in elevation the air inlet conduit extending through said portion of 75 the stack;

Fig. 5 is a sectional view on line 5-5 Fig. 1 viewed downwardly; and,

Fig. 6 is a detail sectional view on curved lines 6-6 illustrated in Fig. 2. 80

The heating apparatus illustrated in the accompanying drawings comprises a hollow base 1, adapted to be mounted on a suitable support and provided with shoulders 2 and 3 to support a fire-box having inner and outer 85 water legs. The base has a rearward extension 4, (see Fig. 4), which communicates with a preferably cylindrical section 5 of a stack, which in turn communicates with a horizontal section 6 leading to an upwardly extending chimney (not shown). 90

Any suitable heating means may be provided. As illustrated the heating means comprises a pipe 7 leading through the front wall 8 of the base 1 to a burner 9 which is illustrated as a Rose burner located within the fire-box, but it will be understood that any form of oil or gas burner may be employed, or that the fire-box may be provided with a 100

suitable grate to support hard fuel such as coal.

Desirably the air, which is admitted to the fire-box to support combustion, is preheated, and for this purpose an air inlet conduit 10 extends downwardly and inwardly through the section 5 of the stack and the extension 4 of the base of the heating apparatus. The end portion of this air inlet conduit 10 desirably is provided with a series of apertures 11 to admit the air, and a cap 12 having a downwardly extending skirt provided with apertures adapted to register with the apertures 11 and which may be adjusted to vary the amount of air admitted into the conduit in accordance with the requirements of the burner.

The fire-box desirably, but not necessarily, is of cylindrical form having an inner wall 13 and a plurality of surrounding walls 14, 15, and 16, parallel to or concentric with the wall 13, depending upon the shape of the fire-box, the space between the walls 13—14 and the space between the walls 15—16 forming respectively inner and outer water legs which desirably surround the fire-box and communicate with each other at the top through conduits 17. The adjacent walls 14 and 15 of the inner and outer water legs 30 provides a flue 18 which communicates with the chamber of the base 1 which communicates with the extension 4 leading to the stack.

Converging conduits 19 extend preferably radially inwardly from the water legs and unite in and communicate with a central column 20 which in turn communicates with other portions of the heating apparatus as will hereinafter more fully appear. The converging conduits 19 in effect form a spider at the upper end of the fire-box upon which suitable heating elements may be superimposed. The liquid to be heated desirably is introduced from a suitable source through an inlet port 21 leading to the lower portion of the outer water leg.

In order to provide sufficient space above the top of the fire-box, which may be said to be represented by the converging conduits 19, one or more wall sections are superimposed upon the water legs of the fire-box and a suitable cover is superimposed upon the upper end of the wall sections. This cover desirably is in the form of a hollow dome 22 having a chamber 23 of suitable capacity and means are provided for causing a communication of said dome with the column 20 at the center of the spider formed by the converging conduits 19. The periphery of the dome desirably is provided with a downwardly extending flange 24 adapted to rest upon the wall 16 of the outer water leg, or preferably upon wall sections superimposed upon said water leg as will herein-65 after more fully appear. The central por-

tion of the base or bottom of the dome 5 desirably is provided with a downwardly extending boss 25 which may rest upon the upper end of the central column 20, or upon suitable sections of heating units which are superimposed thereupon.

The under surface of the bottom of the dome 23 provides a deflector for the ascending flames and products of combustion and serves to direct them outwardly and downwardly into the flue 18 between the inner and outer legs so that the products of combustion pass from the lower ends of the flue 18 into the hollow base 1 of the heating apparatus, thence upwardly through the sections 5 and 6 of the stack to the chimney.

In the preferred embodiment illustrated in Fig. 1 a plurality of wall sections are interposed between the upper ends of the water legs and the bottom of the hollow dome 5. These wall sections are made detachable from the water legs, from each other, and from the dome, so that they can be readily assembled, removed or replaced. Desirably these wall sections are similar and a description of one will serve as a description for both, or for any desired superimposed number. Each wall section comprises a hollow outer wall 26 and a hollow inner wall 27 which is concentric with the hollow outer wall and spaced apart therefrom to provide a flue 28 therebetween which is in vertical alignment with and communicates with the flue 18 between the inner and outer water legs. The inner and outer hollow walls 26 and 27 may be made separate, but desirably are connected at intervals by horizontal conduits 29, four of such conduits being illustrated herein. The connecting conduits desirably are integral with the hollow inner and outer walls and comprise an upper horizontal passage 30 and a lower horizontal passage 31 which communicate at their ends respectively with the chambers 32 and 33 of the outer and inner conduits. Desirably this connection is provided with a horizontal aperture 34 which establishes communication between adjacent sections of the space or flue 28 which is located between the inner and outer hollow walls, as shown in Fig. 6.

Means are provided for establishing communication between the chambers of the inner and outer walls 26 and 27 and the inner and outer water legs. This is accomplished by providing suitable apertures in the connections 29 between the inner and outer walls to receive push nipples 35 and 36, the push nipples 35 establishing communication between the water legs and both the chambers of the inner and outer walls. Other push nipples 36 establish communication between the chambers of superimposed wall sections, while push nipples 37 may be provided to establish communication between the uppermost of the superimposed hollow wall sec-130

tions and the chamber 23 of the hollow dome 5.

By virtue of this construction a free circulation is provided from the water legs which surround the fire-box upwardly through the superimposed wall sections and the dome. The heated liquid or the vapors therefrom may be delivered through a delivery conduit 38 from the upper portion 10 of the dome.

Any suitable means may be provided for securing the superimposed wall sections and the dome together. Desirably similar lugs 39 extend laterally from the water legs, the 15 wall sections and the dome and are secured together by bolts 40. In order to provide a maximum heating surface for the liquid one or preferably a plurality of heating units 41 are superimposed upon the central column 20 20 and connected by push nipples to provide a central conduit leading from the column of the water legs to the dome.

In the preferred embodiment of the invention the heating units comprise a plurality of 25 hollow, preferably radially disposed, chambers 42 extending outwardly from the central column into the space above the fire-box which is enclosed by the wall sections 26 and 27. The central portions of these heating 30 units are provided with annular thickened bosses 43 which engage each other and the lowermost of which rests upon a boss 44 forming the wall of the column 20. The lower wall of the dome 5 is provided with a down- 35 wardly extending boss 45 which rests upon the upper boss 43 of the upper heating unit.

A clamping rod 46, which is secured at its lower end upon a thickened portion or boss 47 centrally of the spider, has at its upper 40 end a clamping bracket or spider 48 which is engaged by a nut 49 upon the upper end of the rod. Push nipples 50, which are respectively forced into cylindrical apertures in the bosses 43, 44, and 45, serve to provide a 45 central conduit leading directly from the water legs to the dome and communicating with each of the superimposed heating units.

By virtue of the construction above described a sectional heating apparatus is provided which can be readily constructed and assembled and in which the parts may be readily removed and replaced. A maximum heat-absorbing surface is presented to the flames and the products of combustion.

In the operation of the device liquid may be introduced at a predetermined rate through the inlet 21 into the outer water leg from which it will circulate through the inner and outer water legs and will thence 55 pass upwardly into the dome through the central hollow column by virtue of the greater heat applied to the water through the walls 19 of the spider and the heating units 27.

The water from the dome will circulate downwardly through the chambers of the side 60

walls into the water legs, thereby providing a continuous circulation of liquid. The flames and the products of combustion rising from the fire-box surround the walls of the chambers 42 of the heating units and impinge 70 upon the bottom of the dome 5, thereby supplying a large amount of heat to the liquid in the chamber of the dome. The products of combustion are deflected by the bottom of the dome downwardly through the flues 28 of the 75 wall section thence into the flue 18 and pass therefrom through the hollow base 4 of the heating apparatus and thence through the stack to the chimney. The heat from the hot products of combustion, during the downward passage through the flue, is absorbed by the liquid in the chambers 32 and 33 of the 80 wall sections and by the liquid in the water legs which surround the fire-box. Thus a maximum amount of heat is absorbed by the 85 liquid from the products of combustion and such heat as passes into the hollow chamber 4 of the base extension and the stack section 5 is largely utilized to heat the air which is supplied to the burner, thereby increasing the 90 efficiency of the burner.

It will be understood that the particular embodiment of the invention disclosed herein is of an illustrative character and is not restrictive, and that various changes in form, 95 construction and arrangement of parts may be made within the spirit and scope of the following claims.

Having thus described the invention, what is claimed as new, and desired to be secured by Letters Patent, is:

1. A sectional liquid heating apparatus comprising a fire-box having a water leg, conduits forming a spider, converging from the upper end of the water leg into a central hollow column, a wall section superimposed upon said water leg comprising inner and outer communicating chambered walls spaced apart to provide a flue therebetween, conduits, communicating with said water leg and the chambers of said wall section, a chambered dome superimposed upon said wall section adapted to direct the products of combustion downwardly into said flue, means respectively establishing communication between said dome and said central column and said water leg, and means to direct the products of combustion from said flue to a stack.

2. A sectional liquid heating apparatus comprising a fire-box having a water leg, conduits, comprising a spider converging from the upper end of the water leg into a central hollow column, a heating unit having a plurality of laterally extending chambers communicating with said hollow column, a wall section superimposed upon said water leg comprising inner and outer chambered walls spaced apart to provide a flue therebetween, conduits communicating with said water leg and the chambers of said wall sections, a

chambered dome superimposed upon said wall sections and communicating with the chambers of said wall sections and said central hollow column and having means to direct the products of combustion downwardly into said flue, and means for directing the products of combustion from said flue to a stack.

3. A sectional liquid heating apparatus comprising a fire-box having a water leg, conduits forming a spider converging from the upper end of said water leg into a central hollow column, a plurality of superimposed detachably connected wall sections superimposed upon said water leg comprising inner and outer communicating chambered walls spaced apart to provide a flue therebetween, a chambered dome superimposed upon the upper wall section, adapted to direct the products of combustion downwardly to said flue, a heating unit mounted upon said spider having radially extending chambers communicating with said hollow column, and means respectively establishing communication between said dome and said hollow column and the chambers of said wall sections and said water leg, and means for conducting the products of combustion from the flue to a stack.

30 4. A sectional liquid heating apparatus comprising a fire-box having a water leg, conduits forming a spider converging from the upper end of said water leg into a central hollow column, a plurality of superimposed 35 detachably connected wall sections superimposed upon said water leg comprising inner and outer communicating chambered walls spaced apart to provide a flue therebetween, a chambered dome superimposed upon the upper wall section adapted to direct the products of combustion downwardly to said flue, a heating unit mounted upon said spider and having radially extending chambers communicating with said hollow column, push 40 nipples respectively connecting said dome to said hollow column and said wall sections to said dome and to said water leg, and means for conducting the products of combustion from the flue to a stack.

50 5. A sectional liquid heating apparatus comprising a fire-box having inner and outer water legs spaced apart to provide a flue therebetween, conduits, forming a spider, converging from the upper ends of said water legs into a central hollow column, a wall section superimposed upon the outer water leg, a chambered dome superimposed upon said wall section adapted to direct the products of combustion downwardly to said flue, a heating unit presenting a large surface area and having a plurality of liquid-containing chambers mounted upon said spider and communicating with said central column and said dome, a delivery conduit leading from said

dome, and a stack communicating with the lower end of said flue.

6. A sectional liquid heating apparatus comprising a hollow base, a stack communicating therewith, a fire-box supported on said hollow base having inner and outer surrounding water legs spaced apart to provide a flue therebetween communicating with said hollow base, conduits, forming a spider, converging from the upper end of said water legs into a central hollow column, a wall section superimposed upon the outer water leg, a chambered dome superimposed upon said wall section adapted to direct the products of combustion downwardly to said flue, a heating unit having a plurality of laterally extending chambers communicating with said central column and said dome, and a delivery conduit leading from said dome.

7. A sectional liquid heating apparatus comprising a fire-box having inner and outer surrounding water legs spaced apart to provide a flue therebetween, conduits, forming a spider, converging from the upper end of said water legs into a central hollow column, a wall section comprising inner and outer communicating chambered walls spaced apart and superimposed upon said water legs with the space between said walls forming a continuation of said flue, conduits communicating with said water legs and the chambers of said walls, a chambered dome superimposed upon said wall section adapted to direct the products of combustion downwardly to said flue, a heating unit mounted upon said spider, and means for conducting liquid from said water legs to said heating unit and said dome.

8. A sectional liquid heating apparatus comprising a fire-box having inner and outer surrounding water legs spaced apart to provide a flue therebetween, conduits, forming a spider, converging from the upper end of said water legs into a central hollow column, a plurality of wall sections each comprising inner and outer communicating chambered walls spaced apart and superimposed upon said water legs with the space between said walls forming a continuation of said flue, conduits communicating with said water legs and the chambers of said wall sections, a chambered dome superimposed upon said wall sections adapted to direct the products of combustion downwardly to said flue, a plurality of superimposed heating units mounted upon said spider, means for conducting the liquid from said water legs to said heating units and said dome, and a delivery conduit leading from said dome.

9. A sectional liquid heating apparatus comprising a fire-box having inner and outer surrounding water legs spaced apart to provide a flue therebetween, conduits, forming a spider, converging from the upper end of said water legs into a central hollow

column, a plurality of superimposed, detachably connected, wall sections comprising inner and outer communicating chambered walls spaced apart, and superimposed upon, and detachably connected to said water legs with the space between said walls forming a continuation of said flue, push nipple conduits communicating with said water legs and the chambers of said walls, a chambered dome superimposed upon said wall adapted to direct the products of combustion downwardly to said flue, a heating unit mounted upon said spider, and push nipples respectively connecting said heating unit to said central column and to said dome.

10. A sectional liquid heating apparatus comprising a fire-box having inner and outer surrounding water legs spaced apart to provide a flue therebetween, conduits, forming a spider, converging from the upper end of said water legs into a central hollow column, a wall section comprising inner and outer chambered walls spaced apart and superimposed upon said water legs with the space between said walls forming a continuation of said flue, a plurality of conduits integral with and connecting said inner and outer walls, push nipples communicating with said water legs and said conduits, a chambered dome communicating with said central hollow column and superimposed upon said wall section adapted to direct the products of combustion downwardly to said flue, means for conducting liquid from said water legs to said dome, and a delivery conduit leading from said dome.

11. A sectional liquid heating apparatus comprising a fire-box having inner and outer surrounding water legs spaced apart to provide a flue therebetween, conduits, forming a spider, converging from the upper end of said water legs into a central hollow column, a wall section comprising inner and outer chambered walls spaced apart and superimposed upon said water legs with the space between said walls forming a continuation of said flue, a plurality of conduits integral with and connecting said inner and outer walls, and having apertures extending horizontally therethrough communicating with the space between said walls, push nipples communicating with said water legs and said conduits, a chambered dome superimposed upon said wall section adapted to direct the products of combustion downwardly to said flue, a push nipple communicating with said hollow column and said dome, means for conducting liquid from said water legs to said dome, and a delivery conduit leading from said dome.

12. A sectional liquid heating apparatus comprising a fire-box having inner and outer surrounding water legs spaced apart to provide a flue therebetween, conduits, forming a spider, converging from the upper end of

said water legs into a central hollow column, a wall section comprising inner and outer chambered walls spaced apart and superimposed upon said water legs with the space between said walls forming a continuation of said flue, a plurality of conduits integral with and connecting said inner and outer walls, push nipples communicating with said water legs and said conduits, a chambered dome superimposed upon said wall section adapted to direct the products of combustion downwardly to said flue, a heating unit mounted upon said spider, push nipples respectively connecting said heating unit to said central column and said dome, and a delivery conduit leading from said dome.

13. A sectional liquid heating apparatus comprising a hollow base, a stack communicating therewith, a fire-box supported on said hollow base having inner and outer surrounding water legs spaced apart to provide a flue therebetween communicating with said hollow base, an air inlet conduit extending through a section of said stack and communicating with said fire-box, conduits, forming a spider, converging from the upper end of said water legs into a central column, a hollow dome supported upon said water legs, having means communicating with said hollow column, means for conducting water from said water legs to the chamber of said dome, and a delivery conduit leading from said dome.

14. A sectional liquid heating apparatus comprising a fire-box having inner and outer surrounding water legs spaced apart to provide a flue therebetween, conduits, forming a spider, converging from the upper end of said water legs into a central hollow column, a plurality of superimposed wall sections comprising inner and outer communicating chambered walls spaced apart and superimposed upon said water legs with the space between said walls forming a continuation of said flue, conduits communicating with said water legs and the chambers of said walls, a chambered dome superimposed upon said wall sections adapted to direct the products of combustion downwardly to said flue, a plurality of heating units superimposed upon said spider, push nipples connecting said heating units together and to said column and said dome, a clamping rod anchored at its lower end in said spider and having at its upper end means detachably engaging the under wall of said dome adapted detachably to clamp said dome, heating units and spider together.

In testimony whereof, I have signed my name to this specification.

WILLIAM A. CROSS.
